UNITED STATES PATENT OFFICE

2,208,824

VIOLA AND VIOLIN SHOULDER REST PAD

Herman Weinberg, Philadelphia, Pa.

Application December 5, 1939, Serial No. 307,580

3 Claims. (Cl. 84—280)

This invention relates to new and useful improvements in protective padding particularly to that type used by concert violinists to protect their shoulder muscles from becoming fatigued, due to long and arduous playing over a long time, and to permit the violin or such similar musical instrument to rest properly in the proper position on the shoulder. It has heretofore been the practice of violinists to protect the shoulder muscles with such awkward padding as handkerchiefs, etc. This was found unsatisfactory due to the shifting of such pad from its initial placement. Certain pads were also made with attachments like rubber bands, or straps, or even adhesives, which were and are still found to be unsatisfactory from the player's standpoint.

The principal object of the present invention is to provide a pad shaped to fit the contour of the shoulder muscles, and the said pad may be securely fastened to the violin in any advantageous position, depending upon the wish and desire of the player.

Another object of the present invention is to provide a pad of the type described which may be readily adjusted as to height with regards to the instrument used and the shoulder upon which it may rest.

While another object of this invention is to provide a pad of the type described, having a flexible connection between the said pad and a novel fastening device. These and other objects of the invention will become apparent from the illustrations of the drawing accompanying these specifications of which:

Figure 1 is a view perspective of a pad made in accordance with my invention shown in its operative position with respect to the violin and player. The violin is shown in phantom or dotted lines to better illustrate the invention. This would also apply if the instrument were a viola.

Figure 2 is a view perspective of a pad made in accordance with the present invention.

Figure 3 is a sectional view taken on line 3—3 of Figure 2.

Figure 4 is a sectional view similar to Figure 3 showing a modified form of construction.

Figure 5 is a fragmentary sectional view similar to Figure 3, showing a still further modified construction.

Referring now more particularly to Figures 1 and 2 of the drawing, the reference numeral 10 designates a pad of soft pliable rubber, the underside 11 of which is formed or moulded to snugly fit the shoulder of the operator of the musical instrument, the violinist in this instance. The

upper side 12 is formed flat having a metallic fitting 13 embedded in the pad 10, as shown, and pivotally receives a ball point connection 14 of a shaft 15 which is threaded engaged in the metallic insert 16 of a gum rubber suction cup member 17, as shown clearly in Figures 2 and 3 of the drawing. In Figure 4 I have shown a pad 10 identical in detail to that shown in Figures 2 and 3, providing a means of adjustment as regards the height of the suction cup 17 with respect to the flat upper side 12 of the pad. This is accomplished by providing in the fitting 13 screw threads 18 to receive therein the thread shank 19 which is fixedly secured to the underside of the suction cup 17, locking nuts 20 are provided on shank 19 to lock said shank after the desired adjustment has been decided upon by the operator of the musical instrument, the violinist in this instance.

In Figure 5 I have shown a modification of the present invention in which the suction cup 17 is by screw threads affixed to the pad by a short shank 21. In this modification the cup is not vertically adjustable with respect to the pad 10. In using the invention the pad is placed on the shoulder in a decided position for playing, the violin or viola is placed in an advantageous playing position by the player, the violin or viola is then forced down on the suction cup 17 firmly grasping the underside of the violin as shown in all the figures of the drawing, particularly in Figure 1 thereof.

The present invention has been found very effective in use and when a desired sitting has been decided upon the violin or viola may be placed in a case without disturbing the pad and its adjustment on the violin.

While I have shown and described preferred embodiments of my invention, it is understood that I am not limited thereto, except within the scope of the annexed claims.

What I claim and desire to secure by Letters Patent is as follows:

1. A protective pad adapted to serve as a cushion between musical instruments, such as a violin, and the shoulder of the player of the musical instrument, a suction cup adapted to be affixed to the underside of the musical instrument, means for joining said suction cup to said protective pad, and said means including a screw-threaded stud 45 cooperable with a nut-like member whereby said means is vertically adjustable.

2. A protective pad adapted to serve as a cushion between musical instruments, such as a violin, and the shoulder of the player of the musical 50 instrument, the violinist in this instance. The 55

instrument, a suction cup adapted to be affixed to the underside of the musical instrument, means for joining said suction cup to said protective pad, said means including a screw-threaded stud 5 cooperable with a nut-like member whereby said means is vertically adjustable, and said means including a pivotal connection between said suction cup and said pad.

3. A protective pad adapted to serve as a cushion 10 between musical instruments, such as a violin,

and the shoulder of the player of the musical instrument, a suction cup adapted to be affixed to the underside of the musical instrument, means for joining said suction cup to said protective pad, said means including a screw-threaded stud 5 cooperable with a nut-like member whereby said means is vertically adjustable, and said means including a permanently fixed member between said suction cup and said pad.

HERMAN WEINBERG. 10
